(57) CLAIM

The ornamental design for a bookmark, as shown and described.

DESCRIPTION

FIG. 1 is a front elevated view of a bookmark showing my new design.

FIG. 2 is a rear elevated view of the bookmark.

FIG. 3 is a side elevated view of the bookmark; and, FIG. 4 is a top end view of the bookmark.

The indicia depicted by means of broken lines in FIG. 1 has been shown for illustrative purposes only and forms no part of the claimed design.
